UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed November 15, 1923. Serial No. 674,899.

My invention relates to engine starters for the starting of engines such as an internal combustion engine, and more particularly to that part of such system known as the drive or transmission which transmits the power of a prime mover such as an electric motor to a member of the engine to be started such as the flywheel thereof. In the present embodiment of my invention, a driving member such as a pinion is adapted to be manually meshed with the flywheel and to be automatically disengaged therefrom when the engine starts on its own power. This pinion is adapted to be subjected to a yielding pressure such as spring pressure and the object of my invention is to provide for the pinion a spring pressure which shall be variable according to the different phases of operation in the cycle of operation of the drive. In particular, the spring means is adapted to exert its maximum pressure against the pinion for the purpose of returning the same to a normal position after being disengaged from the flywheel and its minimum pressure (according to one form), or none at all (according to another form), at the time when the engine starts on its own power and the pinion is being disengaged.

In the drawings, Figure 1 is a sectional elevation of a starting system embodying my invention showing the normal or disengaged position of the parts in full lines and the operated or engaged position in dotted lines; Fig. 2 is a similar view but illustrating cranking position with the spring withdrawn and before disengagement of the pinion; Fig. 3 a sectional elevation illustrating cranking position before the spring is withdrawn from the pinion; Fig. 4 a detail view of one of the spring abutments; Fig. 5 a side view of one of the springs; Fig. 6 a plan view thereof; Fig. 7 a section of the pinion; Fig. 8 a sectional elevation of a modified form of construction; and Fig. 9 a detail view of one of the spring abutments alone.

For the sake of a clear and definite description of my invention, I have shown the same incorporated in a drive of the outboard type and also of the direct drive type, but it will be understood that such invention is applicable also to the inboard type and also to the indirect type of drive.

Referring to the particular embodiment

of my invention as shown in Figs. 1 to 7, the prime mover is here an electric motor 1 having an extended armature shaft 2 provided at its outer end with a suitable bearing 3. A hollow shaft or sleeve 4 is mounted upon the driving or armature shaft for longitudinal movement thereof and rotary movement therewith through the medium of longitudinal splines 5 on the armature shaft which are engaged by the bore of the hollow shaft. This latter shaft is provided with screw threads 6 and may, therefore, be called a screw shaft. This screw shaft is provided at its inner end as a separate or integral part thereof with a sleeve extension having parallel flanges 7, forming between them a circumferential groove 8 with which cooperates a roller 9 of a shifting means which may be of any suitable character but which as shown is a lever 10 pivoted at 11 and actuated by the operator by hand or foot.

The driving member is here in the form of a pinion 12 which is adapted to mesh with the teeth of the engine flywheel 13. It is threaded upon the screw shaft for longitudinal movement thereof and rotary movement therewith and is normally held spring pressed against a stop nut 14 at the outer end of the screw shaft. The spring means, about to be described, cooperates with the pinion in the manner stated and also to return the pinion to normal position against the stop nut after being automatically demeshed from the flywheel. The object of my invention is to provide a spring means which shall perform these functions and at the same time not interfere with the freedom of movement of the pinion during its demeshing operation.

To this end, I provide a series of springs 15 which are looped at their centers around the grooved middle portions of weighted buttons 16 in the form of small dumb-bells. The outer ends of these springs are connected in a suitable way as by means of pivot pins 17 to two spring abutment plates 18 and 19 respectively. The plate 18 is adjacent the inner face of the pinion 12 and when the parts are in the normal position as shown in full lines in Fig. 1 such plate bears with a light pressure against the pinion and holds the same in its normal position against the stop nut 14. The other plate 19 fits over the screw shaft and is

positioned against a drum or flange sleeve the pinion to its normal position against the stop nut.

My drive also includes means for catching and holding the pinion in retracted position on the screw shaft after being demeshed from the flywheel and preventing the pinion from contacting the flywheel in case the screw shaft should be left in shifted position after the engine has been started. Such means 10 which are shown in Fig. 3, comprise a latch 21 pivoted in a longitudinal slot 22 in the screw shaft and adapted to engage a notch 23 in the bore of the pinion, Fig. 7. Normally the outer end of the latch lies in a 15 groove between two of the splines 5 of the armature shaft and the inner end bears against the periphery of such armature shaft. When the screw shaft is shifted to the left the inner end of the latch will ride 20 down the slope 24 at the inner end of such groove by reason of the pressure of the spring 25, with the result that the outer end of the latch will be moved radially to operative position to engage the notch 23 when the 25 pinion is within the range of the latch. Upon demeshing, the pinion moves longitudinally inwardly on the screw shaft and is caught by the latch and thereby prevented from returning to normal position until the 30 latch is actuated to release it in the manner hereinafter explained.

Describing a cycle of operation and beginning with the parts in their normal position shown in full lines in Fig. 1, the operator 35 by actuating the shifting means shifts the drive assembly to the left, bringing the pinion 12 into mesh with the flywheel gear. Thereupon either by independent operation or automatically as an incident to the final 40 operation of the shifting means, the current is supplied to the motor thereby rotating the screw shaft and its pinion and rotating the flywheel. Thereupon by centrifugal action the buttons 16 will be thrown outwardly and 45 the springs and the plates 18 and 19, will assume the position shown in Fig. 2. In particular, the plate 18 will be withdrawn from the path of demeshing movement of the pinion with the result that the pinion is 50 now free to move to the right with perfect freedom when automatically demeshed as a result of the operation of the engine on its own power. The pinion will now be caught by the latch 21 and held in retracted position until the next phase of operation.

Then when the shifting means is released the screw shaft will slide back to normal position, but just before it reaches that position, the inner end of its latch will ride up on the slope 24 and onto the periphery of the armature shaft, thereby releasing the latch from the pinion. At this time the springs 55 are at maximum tension and in their restoration to normal condition as the motor slows down, such springs will forcibly thrust

In Figs. 8 and 9, I have shown a modified form of construction according to which pivoted arms cooperating with a coiled spring perform the function of the springs 15 above described. In this modified form, a series of links 21 are pivoted to each other at their adjacent ends and at their outer ends to plates 22 and 23. The plate 23 is adapted to slide freely upon the screw shaft and the same forms a movable abutment for a coil spring 24 which is interposed between it and a spring abutment 25 carried by the pinion. The links are held in normal extended position as shown in full lines in Fig. 8 by means of a truncated conical shell 26 which is secured within the casing 27. This casing forms the bearing for the drive and also for the shifter mechanism and the same is attached to one end of the starting motor frame.

Describing a cycle of operation of the parts shown in Fig. 8 beginning with the same in their normal position shown in full lines the operator shifts the drive assembly in the manner hereinbefore described, thereby bringing the pinion into mesh with the flywheel. As a result of this movement, the pressure of the spring will buckle the links to the dotted line position shown in Fig. 8 due to the relief from the shell 26 and the pressure of the coil spring 24 against the abutment 23 thereby moving such abutment to the right against the edge of the drum 28. In this manner, the pressure of the coil spring against the pinion will be relieved so that when the pinion is automatically demeshed it will not encounter any material resistance to its longitudinal movement, but when the operator releases the shifting means and the screw shaft is returned to normal position the shell 26 will straighten out the links to their normal position and as a result an increased pressure will be imparted to the pinion by reason of the compression of the coil spring. The pinion will thereupon be returned to normal position against its stop nut. The same kind of latch means is here used as in the other form of construction.

I do not herein broadly claim the construction and the arrangement of the drive including the longitudinally shiftable sleeve or driving member or pinion thereon and the catch device for holding the pinion in demeshed position while the screw shaft or sleeve is still shifted to cranking position as the same represent subject matter of my prior applications for patent including application filed on January 4, 1923, Serial No. 610,672, the present application being directed to the particular invention pointed out in the claims herein.

I claim:

1. An engine starter drive including a

- rotatable shaft, a driving member mounted thereon for rotary movement therewith and for longitudinal movement thereof, yielding means acting on the driving member tending 5 to hold it to a normal position on the shaft, and speed responsive means for varying the degree of pressure exerted by the yielding means on the driving member without affecting the position of the latter on the shaft.

10 2. An engine starter drive including a rotatable shaft, a driving member mounted thereon for rotary movement therewith and for longitudinal movement thereof, yielding means acting on the driving member tending 15 to hold it to a normal position on the shaft, and centrifugal means acting upon the yielding means for varying the degree of pressure exerted thereby on the driving member without affecting the position of the latter on the shaft.

20 3. An engine starter drive including a rotatable shaft, a driving member mounted thereon for rotary movement therewith and for longitudinal movement thereof into engagement with a member of the engine to be started and for automatic disengagement therefrom, yielding means acting on the driving member tending to hold it to a normal position on the shaft, and speed responsive means physically independent of the driving member for varying the degree of pressure exerted by the yielding means on the driving member.

25 4. An engine starter drive including a rotatable shaft, a driving member mounted thereon for rotary movement therewith and for longitudinal movement thereof into engagement with a member of the engine to be started and for automatic disengagement 30 therefrom, yielding means acting on the driving member tending to hold it to a normal position on the shaft, and centrifugal means physically independent of the driving member and acting upon the yielding means for varying the degree of pressure exerted thereby on the driving member.

35 5. An engine starter drive including a rotatable shaft, a driving member mounted thereon for rotary movement therewith and for longitudinal movement thereof, yielding means acting on the driving member tending 40 to hold it to a normal position on the shaft, and comprising a spring, and speed responsive means cooperating therewith for varying the degree of pressure exerted thereby on the driving member without affecting the position of the latter on the shaft.

45 6. An engine starter drive including a rotatable shaft, a driving member mounted thereon for rotary movement therewith and for longitudinal movement thereof, yielding means acting on the driving member tending 50 to hold it to a normal position on the shaft, and comprising a spring, and a cen-

trifugal weight cooperating therewith for varying the degree of pressure exerted thereby on the driving member without affecting the position of the latter on the shaft.

70 7. An engine starter drive including a rotatable shaft, a driving member mounted thereon for rotary movement therewith and for longitudinal movement thereof, yielding means acting on the driving member tending 75 to hold it to a normal position on the shaft, and comprising a series of springs mounted on the shaft, and centrifugally operating weights on said springs.

80 8. An engine starter drive including a rotatable shaft, a driving member mounted thereon for rotary movement therewith and for longitudinal movement thereof, yielding means acting on the driving member tending 85 to hold it to a normal position on the shaft, and comprising a series of springs mounted on the shaft, a spring abutment connected with one end of said springs and movable longitudinally in the path of movement of the driving member, and speed responsive means for controlling said movement of the abutment.

90 9. An engine starter drive including a rotatable shaft, a driving member mounted thereon for rotary movement therewith and for longitudinal movement thereof, yielding means acting on the driving member tending 95 to hold it to a normal position on the shaft and comprising a series of springs mounted on the shaft, a spring abutment connected with one end of said springs and movable longitudinally in the path of movement of the driving member, and centrifugally operating weights on said springs for moving said abutment longitudinally.

100 10. An engine starter drive including a rotatable shaft, a driving member mounted thereon for rotary movement therewith and for longitudinal movement thereof, yielding means acting on the driving member tending 105 to hold it to a normal position on the shaft and comprising a series of springs mounted on the shaft and having center loops, and weighted buttons fastened to said loops.

110 11. An engine starter drive including a rotatable shaft, a driving member mounted thereon for rotary movement therewith and for longitudinal movement thereof, yielding means acting on the driving member tending 115 to hold it to a normal position on the shaft and comprising a series of springs, two parallel spring abutments, one of which is rigidly secured to the shaft and the other of which is movable longitudinally thereof, and centrifugally operating weights secured 120 to said springs.

120 12. An engine starter drive including a rotatable shaft, a driving member mounted thereon for rotary movement therewith and for longitudinal movement thereof, yielding 125 means acting on the driving member tending to hold it to a normal position on the shaft, and comprising a spring, and a cen-

- means acting on the driving member tending to hold it to a normal position on the shaft and comprising a series of springs, two parallel spring abutments, one of which is rigidly secured to the shaft and the other of which is movable longitudinally thereof, said springs being pivotally attached at their ends to said abutments, and centrifugally operating weights secured to said springs.
- 10 13. An engine starter drive including a rotatable shaft, a driving member mounted thereon for rotary movement therewith and for longitudinal movement thereof, yielding means acting on the driving member tending to hold it to a normal position on the shaft and comprising spring means and a longitudinally movable spring abutment connected therewith and movable relative to the driving member, and speed responsive means for moving such abutment longitudinally and thereby varying the degree of pressure exerted by the spring means upon the driving member.
14. An engine starter drive including a rotatable shaft, a driving member mounted thereon for rotary movement therewith and for longitudinal movement thereof, yielding means acting on the driving member tending to hold it to a normal position on the shaft and comprising spring means and a longitudinally movable spring abutment connected therewith and movable relative to the driving member, and centrifugally operated weights cooperating with the abutment and spring for varying the degree of pressure exerted by the spring means upon the driving member.
15. An engine starter drive including a rotatable shaft, a driving member mounted thereon for rotary movement therewith and for longitudinal movement thereof, yielding means acting on the driving member tending to hold it to a normal position on the shaft and comprising a spring and two spring abutments with which the spring cooperates, one of the abutments being secured to the shaft and the other movable longitudinally thereof, and speed responsive means cooperating with said spring.
16. An engine starter drive including a rotatable screw-threaded shaft, a pinion threaded thereon for rotary movement thereof and for longitudinal movement thereof and adapted to engage a member of the engine to be started, said shaft having a stop against which the pinion is normally positioned, and speed responsive yielding means adapted to return the pinion to its said normal position but not interfering with its longitudinal movement on the screw shaft in its demeshing operation, and also including means for temporarily holding the pinion in retracted position on the shaft after disengagement.
17. An engine starter drive including a rotatable shaft, a driving member mounted thereon for rotary movement therewith and for longitudinal movement thereof, and
- adapted to engage a member of the engine to be started, speed responsive controlled yielding means acting on the driving member to restore it to normal position on the shaft, and means for temporarily holding the driving member in retracted position on the shaft after its disengagement from the engine member.
18. An engine starter drive including a rotatable shaft, a driving member mounted thereon for rotary movement therewith and for longitudinal movement thereof, and adapted to engage a member of the engine to be started, speed responsive controlled yielding means acting on the driving member to restore it to normal position on the shaft, said shaft being mounted also for longitudinal movement, and means controlled by the longitudinal movement of the shaft for temporarily holding the driving member in retracted position on the shaft after its disengagement from the engine member.
19. An engine starter drive including a rotatable shaft, a driving member mounted thereon for rotary movement therewith and for longitudinal movement thereof, and adapted to engage a member of the engine to be started, speed responsive controlled yielding means acting on the driving member to restore it to normal position on the shaft, said shaft being mounted also for longitudinal movement, and means controlled by the longitudinal movement of the shaft for temporarily holding the driving member in retracted position on the shaft after its disengagement from the engine member, said holding means comprising a latch pivoted on the shaft and, in its operative position adapted to engage the driving member when in range thereof.
20. An engine starter drive including a rotatable screw-threaded shaft, a pinion threaded thereon for rotary movement thereof and for longitudinal movement thereof and adapted to engage a member of the engine to be started, said shaft having a stop against which the pinion is normally positioned, and speed responsive yielding means adapted to return the pinion to its said normal position but not interfering with its longitudinal movement on the screw shaft in its demeshing operation, and also including means for temporarily holding the pinion in retracted position on the shaft after disengagement.
21. An engine starter drive including a rotatable screw-threaded shaft, a pinion threaded thereon for rotary movement thereof and for longitudinal movement thereof and adapted to engage a member of the engine to be started, said shaft having a stop against which the pinion is normally positioned, and speed responsive yielding means adapted to return the pinion to its said normal position but not interfering with its

longitudinal movement on the screw shaft in its demeshing operation, and also including means for temporarily holding the pinion in retracted position on the shaft after 5 disengagement, such holding means comprising a latch pivoted on the shaft, and, in its operative position adapted to engage the pinion when in range thereof.

22. An engine starter drive including a 10 rotatable shaft, a driving member mounted thereon for rotary movement therewith and for longitudinal movement thereof, yielding means acting on the driving member tending to hold it to a normal position on the shaft, 15 and speed responsive means for removing the pressure of such yielding means upon the driving member.

23. An engine starter drive including a 20 rotatable shaft, a driving member mounted thereon for rotary movement therewith and for longitudinal movement thereof, a longi-

tudinally movable spring abutment, a coil spring bearing at one end against the driving member and tending to hold it to a normal position on the shaft and at its other end 25 against said abutment, and speed responsive means for controlling the longitudinal position of such abutment for removing the pressure of the spring upon the driving member.

24. An engine starter drive including a rotatable driving shaft, a sleeve mounted to slide longitudinally upon said shaft and to be rotarily driven thereby, yielding means acting on the driving member tending to hold it to a normal position on the sleeve, speed responsive means for removing the pressure of such yielding means upon the driving member, and means for sliding the sleeve upon said shaft.

WILLIAM L. McGRATH.
